UNITED STATES PATENT OFFICE.

HERBERT R. MOKLER, OF BRADFORD, ILLINOIS.

CLAMP.

1,403,808.

Specification of Letters Patent. Patented Jan. 17, 1922.

Application filed October 27, 1920. Serial No. 420,048.

To all whom it may concern:

Be it known that I, HERBERT R. MOKLER, a citizen of the United States, and a resident of Bradford, in the county of Stark and State of Illinois, have invented certain new and useful Improvements in Clamps, of which the following is a specification.

My invention is an improvement in clamps, and has for its object to provide a device of the character specified, especially designed for holding objects to be ground or polished of irregular form, such, for instance, as plowshares, cultivator shovels, tower knives, harrow blades, planter knives, and the like, wherein there is provided a body member having a pair of fixed stops or abutments spaced apart from each other, and having a clamp movable between the abutments and provided with means for clamping the article between the clamp and the body member.

In the drawings,

Figure 1 is a perspective view of the improved clamp,
25 Figure 2 is a top plan view,
Figure 3 is a front view,
Figure 4 is a section on the line 4—4 of Figure 3,
Figure 5 is a perspective view of the 30 clamping lever.

In the present embodiment of the invention, a body member is provided, in the form of a plate 1, having secured transversely of one end thereof an abutment 2, in the form 35 of a block, and having secured transversely thereof near the other end a second abutment 3, in the form of a block. The plate 1, and the blocks 2 and 3 may be of wood or other suitable material, and beyond the 40 abutment 3, the plate is reduced to form a handle 4, for convenience in handling the clamp as a whole. The abutments 2 and 3 are secured to the plate by means of screws 5, 4 screws being used to connect the block 45 2, while 2 screws are used to connect the block 3.

The clamping member, which is adjustable longitudinally of the plate between the abutments, is in the form of a yoke comprising a body 6, which is arranged transversely of the plate, and arms 7 extending laterally from the body on opposite sides of the plate and upwardly above the level of the tops of the abutments, and these arms are threaded, 55 as shown.

The yoke is clamped to the plate by means

of a clamping plate 8, which is arranged transversely of the plate above the same, and has openings to receive the arms 7. Nuts 9 are threaded on to the arms above the plate 60 8, and it will be evident that by turning the nuts in the proper direction, the plate 8 may be clamped on the plate 1 to firmly clamp the yoke to the said plate. This plate 8, as shown more particularly in Figure 2, 65 is approximately diamond-shaped, being of greatest width at its center and gradually decreasing in width toward each end.

The elements just described, namely, the yoke of the plate 8, constitute what is in 70 effect the fixed jaw of the clamp. The movable jaw is constituted by a lever 10, which is hinged to a nut 11, adjustable on one of the arms 7, and this lever has intermediate its ends a notch 12 for receiving the other 75 arm. A handled nut 13 is threaded on to the said other arm of the yoke, to engage above the lever 10, to hold the said lever in adjusted position. The nut 11, which is rectangular in cross-section, has the opening for 80 the arm 7 at one end. The other end is received between the arms 14 of a fork on the lever, and a bolt 15 is passed through registering openings in the arms and in the nut, and is engaged by a nut to pivotally 85 connect the lever to the nut 11.

Referring to Figures 1, 2 and 4, it will be seen that the abutment 2 has, in the upper face thereof, and at that edge adjacent to the abutment 3, a notch or recess 15. This 90 notch, or recess, is inclined with respect to the long axis of the plate 1. The corners of the notch 12 of the handle 10 are beveled to facilitate the engagement of the lever beneath the nut 13.

95 In operation, when it is desired to clamp a plow, for instance, the plow is placed in the clamp between the abutments 2 and 3. It is clamped to the plate by means of the handle, the nuts 11 and 13 being adjusted 100 to obtain the proper pressure to hold the same firmly. Now the operator grasps the end of the lever 10 and that arm 7 of the element 6—7 which is remote from the grip portion of the lever, and applies his knee 105 against the other end of the plate 1. He may thus hold the plow, or other article firmly against the stone, to grind or polish the plow without placing his hands near the point of danger, and without any possibility of being 110 burned by the heating of the plow. Because of the fact that a very great pressure

may be exerted, the grinding or polishing will be quicker than were the operator merely grasping the article to be polished or ground.

5. I claim:—

1. A device of the character specified, comprising a body member having at one end a handle, a pair of abutments secured to the body in spaced relation, and a clamp 10 between the said members for clamping the article to be handled, said clamp being adjustable between the abutments, the clamp comprising a yoke consisting of a body extending transversely of the body member, 15 and arms extending upwardly alongside thereof, a plate adjustably connected with the arms above the body member, a nut threaded on to each arm, and a lever pivoted to one nut and having a notch for receiving 20 the other arm beneath the other nut.

2. A device of the character specified, comprising a body member having at one end a handle, a pair of abutments secured to the body in spaced relation, and a clamp 25 between the said members for clamping the article to be handled, said clamp being adjustable between the abutments.

3. A device of the character specified comprising a body member, a pair of abut-

ments carried by the body member in spaced 30 relation and adapted to support the work, a clamp movably mounted on the body member and including a lever directly engageable with the work and means for adjusting said lever, and means for securing the clamp 35 in adjusted position on the body member.

4. A device of the character described comprising a body member, a pair of abutments carried by the body member in spaced 40 relation and adapted to support the work, a clamp movably mounted on the body member and including a yoke, a lever directly engageable with the work, and means for adjustably positioning the lever on the yoke, and means for securing said clamp in adjusted 45 position on the body member.

5. A device of the character described comprising a body member, a pair of abutments carried by the body member and adapted to support the work, a clamp movably mounted on the body member and including a fixed element, a relatively movable work engaging element, and means for adjustably securing the work engaging element on the fixed element of the clamp, and means 50 for securing said clamp in adjusted position on said body member.

HERBERT R. MOKLER.
